JULIUS LEOPOLD AND MORRIS BEBERFELD, OF NEW YORK, N. Y.

CORSET.

1,203,020.

Specification of Letters Patent. Patented Oct. 31, 1916.

Application filed August 11, 1915. Serial No. 44,937.

To all whom it may concern:

Be it known that we, JULIUS LEOPOLD and MORRIS BEBERFELD, a citizen of the United States and a subject of the Czar of Russia, respectively, and both residents of New York, county and State of New York, have invented a certain new and useful Improvement in Corsets, of which the following is a full, clear, and exact specification.

10 This invention relates to a class of apparel adapted to be worn by women.

Our invention has for its object primarily to provide a corset designed to be worn by women whereby the rotundity of an enlarged abdomen will be greatly reduced in a manner so that the pressure thereon will be equalized in order to avoid all tendency to cause excessive strain on parts of the abdomen as is incident to many other forms 20 of corsets, and which is constructed so that the abdomen of the wearer will be comfortably supported as well as tending to yield sufficiently to give the organs of this part of the body proper freedom of movement.

25 Moreover, this form of corset may be advantageously employed to support the abdomen of women following surgical operations on the abdomen, thereby permitting the usual abdominal bandages to be dispensed with. This is accomplished mainly by providing a corset having a body composed of two halves with two front clasp-stays for permitting the corset to be removably applied on the wearer in the usual manner.

35 In the abdominal portion of each half of the body is an elastic reducing element, or gore composed of two sections, the sections of both reducing elements being laced together so that these elements may be adjusted to conform accurately to the shape of the abdomen of the wearer as well as permitting the rotundity of the abdomen to be greatly reduced without discomfiture.

40 Another object of the invention is to provide a retaining element for yieldingly limiting the elastic movements of the reducing elements as well as serving to comfortably support the abdomen of the wearer; and a further object of the invention is to provide 45 a corset of a simple, efficient, and durable construction, and which is susceptible of being made in all sizes and in any desired style.

45 A practical embodiment of the invention is represented in the accompanying drawing forming a part of this specification in

which similar characters of reference indicate corresponding parts in all the views, the said invention being more fully described hereinafter, and then pointed out in 60 the claims at the end of the description.

In the drawing, Figure 1 is a front elevation of one form of the corset embodying our invention, showing the flaps of the retaining element thereof disposed in lateral 65 directions from the body of the corset. Fig. 2 is a front elevation of the corset showing the flaps of the retaining element in position when the corset is in use, and Fig. 3 is a section taken on the line III—III of 70 Fig. 2.

The corset has a body 10 which may be made in any desired style with a high, or low bust, and with long, or short hips. In the drawing the body 10 is illustrated in a 75 prevailing type composed of two similar halves, as 11 and 12, having two detachably connected coöperating clasp-stays 13 and 14, the lower ends of which are preferably fastened together by a well-known form of 80 hook and eye clasp, as 15, and at spaced intervals in each half of the body may be provided a suitable number of vertically disposed reinforcing steel stays 16 and 17 as commonly used in the general makes of corsets. Each of the halves of the body of the corset here shown also has a skirt 18 which is an extension of the outer covering of the half as provided in some styles of corsets to fit over the hips of the wearer, though 90 it is to be understood that the principles of our invention are not confined to any particular design of body.

In the halves of the body of the corset transversely between the clasp-stays 13, 14 95 and the steel stays 16, 17 are reducing elements, or gores 19 and 20 which are preferably similar in formation. Both of these reducing elements may be made of elastic webbing, or other material so as to yield 100 sufficiently when subjected to pressure, and the central parts of both of the elements are vertically slitted to provide two members 21, 21^a and 22, 22^a, respectively, the opposed ends of each pair of the elastic members being eyeleted for permitting the members to be laced together by cords, or the like, as 23 and 24. Both of the reducing elements 19 and 20 are preferably of widths so as to embrace the abdomen of the wearer, and the 110 lengths of the members of the elements are somewhat less than the spaces between the

clasp-stays 13, 14 and the steel stays 16, 17 so as to tend to contract the front space of the body of the corset between the hips when the members of the reducing element are accordingly laced. The rotundity of the abdomen will thereby be proportionately reduced, and by properly lacing the members of the reducing elements they may be adjusted to conform accurately to the shape of the abdomen of the wearer without causing discomfiture.

In practice the corset is applied to the wearer by guiding its body 10 around the waist of the wearer in the usual manner after the clasp-stays 13 and 14 have been detached, and following the proper positioning of the corset the clasp-stays are re-fastened. Should the resilient reducing elements 19 and 20 not be sufficiently taut to reduce the rotundity of the abdomen to a desired size the laces 23 and 24 are tightened in a manner to direct the eyeleted edges of the members of the reducing elements partly, or entirely together so that the elements will conform to the shape of the abdomen as well as reducing it in size. Moreover, by providing the resilient reducing elements in these forms the underneath part of the abdomen of the wearer will be properly supported, and the resiliency of the elements will permit sufficient yielding action to afford perfect comfort to the wearer. While we have shown and described a form of our corset having two of the resilient reducing elements 19 and 20 forms of the corset may be made wherein these reducing elements are dispensed with as occasion requires.

To yieldingly limit the elastic action of the reducing elements 19 and 20 as well as serving to comfortably support the abdomen of the wearer, a retaining element 25 is provided. The retaining element 25 is composed of two flaps 26 and 27 made of cloth, or other flexible material, and both of the flaps are preferably similar in size and shape. Each of the flaps 26 has a body part 28, the opposite ends of these parts being secured to the halves of the body of the corset adjacent to the steel stays 16 and 17 so as to be swung across the reducing elements 19 and 20, and these parts of the flaps are preferably the same widths as the reducing elements while the lower edge of each body part is formed on a downward incline, as shown, so as to accurately conform with the shape of the abdomen when in use. Projecting from the upper portion of the free end of the body part of each of the flaps 26 and 27 is an integral extension or tongue 29 of considerably less width than the body part, and these tongues extend toward each other so as to be disposed in overlapping arrangement when in use, as shown in Fig. 2, as well as being of lengths so that their

ends will slightly overlap the steel stays 16 and 17 of the body of the corset. Interposed in the central part of the tongue of each of the flaps 26 and 27 is a gore 30 of elastic webbing, or other yielding material to permit the flaps to stretch and contract, and centrally of the body part 28 of the flap 27 is a vertically disposed elongated opening 31 for passage of the tongue of the flap 26, and on the body part of the flap 27 is a substantially rectangular plate 32 having an opening of the same size and in register with the opening 31 of this flap, this apertured plate serving to stiffen the body of the flap 27 against sagging downwardly when the flaps of the retaining element are in overlapping arrangement. When the corset has been applied on the wearer, and the reducing elements 19 and 20 have been suitably adjusted by manipulating the laces 23 and 24 to yieldingly draw together, or to loosen the members of these elements as desired, the tongue 29 of the flap 26 is disposed through the opening 31 of the flap 27 so that this tongue will overlap the flap 27. The tongues 29 are then detachably connected to the halves of the body of the corset by two sets of complemental fastening devices 33 and 34. Each set of the fastening devices 33 and 34 consists of two pairs of spaced eyes 35 and 36, one pair being provided on the steel stay 16 of the half 11 of the body of the corset while the second pair of the hooks are arranged on the steel stay 17 of the half 12 of the body of the corset. On the opposed surface of the tongue 29 of the flap 26 are two spaced pairs of spaced hooks 37 and 38 one pair of which are inserted in the pair of eyes 36 to removably hold the flap 26 to the half 11 of the body of the corset, and on a similar surface of the tongue of the flap 27 are also two spaced pairs of spaced hooks 39 and 40 one pair of which are inserted in the pair of eyes 36 to detachably fasten the flap 27 to the half 12 of the body of the corset. The elastic movements of the reducing elements 19 and 20 will then be yieldingly limited, and the abdomen of the wearer will also be comfortably supported.

In order to permit front garters to be used in conjunction with the corset, to the clasp-stay 13 is fastened one end of the loop-strap, as 42, having its other end secured to the lower edge of the body of the flap 26 of the retaining element, and to the clasp-stay 14 is fastened one end of another loop-strap 43 which has its other end held to the lower edge of the body of the flap 27 of the retaining element. Thus by providing this form of corset the rotundity of an enlarged abdomen may be greatly reduced so that the pressure thereon will be equalized to avoid all tendency to cause undue strain on the parts of the abdomen as well as serving to

give the organs of this part of the body of the wearer proper freedom of movement. Furthermore, this form of corset may be advantageously worn by women following 5 surgical operations on the abdomen instead of employing the ordinary forms of abdominal bandages.

In the foregoing description, we have embodied the preferred form of our invention, 10 but we do not wish to be understood as limiting ourselves thereto, as we are aware that modifications may be made therein without departing from the principle, or sacrificing any of the advantages of this 15 invention, therefore we reserve to ourselves the right to make such changes as fairly fall within the scope thereof.

Having thus described our invention, we 20 claim as new and desire to secure by Letters Patent:—

1. A corset with a body composed of two adjustably connected halves each with a yielding abdominal portion, two flexible flap members each with one of its ends held to the hip part 25 of each half of the body so as to be disposed across the abdominal portions of the halves, and one of the flap members having an opening for passage of the other flap member, an elastic gore in each flap member so that the 30 members may be yieldingly expanded and contracted, and complementary fastening devices on the halves of the body and on the flap members whereby the other end of each flap member may be adjustably connected 35 to the hip part of the opposite member of the corset to hold the flap members tightly or comparatively loose across the abdominal portions.

2. A corset with a body composed of two 40 adjustably connected halves each with an elastic gore, two flap members each with one of its ends held to the hip part of each half of the body so as to be disposed in overlapping arrangement across the halves of the 45 body, an elastic gore in each flap member so that the members may yieldingly expand and contract, an apertured plate in one of the flap members for passage of the other flap member, and means whereby the other 50 end of each flap member may be adjustably connected to the opposite half of the body to detachably hold the flap members tightly or comparatively loose across the abdominal portions.

55 3. In a corset with a body composed of

two adjustably connected halves, two flexible flap members each with a body part having one end secured to the hip part of each half of the body so as to be disposed across the abdominal portion of the halves of the body 60 of the corset, and both of the body parts of the flap members being of widths and lengths to embrace the abdominal portion of the corset in overlapping arrangement, an integral tongue extending from the other ends of the 65 body parts of the flap members, and each tongue being of less width than said body parts, an elastic gore in each of the tongues, and the body part of one of the flap members having an opening surrounded with an apertured stiffening plate for passage of the tongue of the other flap member to prevent sagging of the flap members, and means whereby the tongue of each flap member may be adjustably connected to the hip part of 70 the opposite half of the body of the corset.

4. In a corset with a body composed of two adjustably connected halves, two flexible flap members each with a body part having one end secured to the hip part of each half 80 of the body so as to be disposed across the abdominal portion of the halves of the body of the corset and both of the body parts of the flap members being of widths and lengths to embrace the abdominal portion of the 85 corset in overlapping arrangement, an integral tongue extending from the other ends of the body parts of the flap members, and each tongue being of less width than said body parts, an elastic gore in each of the 90 tongues, and the body part of one of the flap members having an opening surrounded with an apertured stiffening plate for passage of the tongue of the other flap member to prevent sagging of the flap members, 95 means whereby the tongue of each flap member may be adjustably connected to the hip part of the opposite half of the body of the corset, and loops depending from the lower edges of the halves of the body as well as 100 from the lower edges of the flap members for the purpose specified.

This specification signed and witnessed this tenth day of August A. D. 1915.
